UNITED STATES PATENT OFFICE.

PAUL PIGNOT, OF YONKERS, NEW YORK, ASSIGNOR TO ALEXANDER SMITH & SONS CARPET COMPANY, OF SAME PLACE.

DESIGN FOR A CARPET.

SPECIFICATION forming part of Design No. 14,031, dated July 3, 1883.

Application filed May 22, 1883. Term of patent 3½ years.

To all whom it may concern:

Be it known that I, PAUL PIGNOT, of Yonkers, Westchester county, State of New York, have invented a new and original Design for 5 Carpets, of which the following is a specification.

The accompanying photograph illustrates my new design for carpets.

This invention relates to a new design for 10 carpets, oil-cloths, and analogous fabrics; and it consists of the new ornamentation of parts herein more fully pointed out.

On a mottled background, A, is the representation, B, of a large and symmetrical group 15 of flowers and leaves, the central part of said group being composed of rose-like flowers *a*, from which radiate bunches, *b*, of smaller flowers, that are set off by leaves *d*. The rose-like flowers *a a* appear to rest on drooping leaves 20 *e*. Above this group B in the photograph is

a fanciful scroll, C, which extends across the breadth of the carpet, and which, when the carpet is matched, will be between four groups, B—that is to say, there will be such a group B above, another below, another at its right, 25 and another at its left, one terminal, *f*, of the scroll C being represented at the right-hand side of the group B, at the lower part thereof, in the photograph. In this scroll C are apparently held, and with it are, to an extent, intertwined, sprays D of flowers, producing a graceful effect.

I claim—

The design for carpets, consisting of figures A B C D *a b d e f*, substantially as shown.

PAUL PIGNOT.
